(57) **CLAIM**

The ornamental design for a headphone amplifier, as shown and described.

DESCRIPTION

1. Headphone amplifier

FIG. 1.1 is a front, top, and left-side perspective view showing the new design; FIG. 1.2 is a front elevation view thereof; FIG. 1.3 is a rear elevation view thereof; FIG. 1.4 is a left side elevation view thereof; FIG. 1.5 is a right side elevation view thereof; FIG. 1.6 is a top plan view thereof; FIG. 1.7 is a bottom plan view thereof; and FIG. 1.8 is a rear, bottom, and right-side perspective view thereof.

The broken lines shown are included for the purpose of illustrating portions of the headphone amplifier that form no part of the claim.

1 Claim, 8 Drawing Sheets
